UNITED STATES PATENT OFFICE.

LELICE E. JOHNSON AND HARRY M. MATHERS, OF WEED, CALIFORNIA; SAID JOHNSON
ASSIGNEE OF ONE-HALF OF THE WHOLE TO CHARLES W. KEIVER, OF OAKLAND,
CALIFORNIA.

PROMER.

1,116,823.

Specification of Letters Patent. Patented Nov. 10, 1914.

Application filed December 27, 1913. Serial No. 809,012.

To all whom it may concern:

Be it known that we, LELICE E. JOHNSON and HARRY M. MATHERS, citizens of the United States, residing at Weed, in the county of Siskiyou and State of California, have invented certain new and useful Improvements in Primers, of which the following is a specification; reference being had to the accompanying drawings.

10 This invention relates to priming devices for internal combustion engines and has for its principal object to produce a simple, efficient and reliable hand operated device of this character particularly designed for use upon motorcycles and similar vehicles, whereby the cylinders of the engine may be properly primed when necessary.

Our invention has for a further and more specific object to provide a spring pressed plunger operating in a suitable cylinder, said cylinder being mounted upon a base, provided with a passage for the gasoline, a connection between the base and the intake manifold of the engine, a connection between the base and the gasoline supply tank, valves arranged in said connections and normally closing communication between the same and the base and adapted to be alternately opened and closed in the movement of the plunger in opposite directions, said plunger being provided with an extension to normally close the passageway in said base, and thereby prevent leakage of the gasoline through the same and the engine cylinders.

35 The invention has for a further object to produce a device for the above purpose which may be easily operated, will occupy but small space upon the vehicle and can be manufactured at comparatively small cost.

With the above and other objects in view, the invention consists in the novel features of construction and the combination and arrangement of parts to be hereinafter more fully described, pointed out in the claim and shown in the accompanying drawings, in which—

Figure 1 is a side elevation of our improved priming device; Fig. 2 is a vertical section thereof, the same connected to the gasoline supply tank and the intake manifold of the engine; Fig. 3 is a section taken on the line 3—3 of Fig. 2.

Referring in detail to the drawings, 5 5 designates a suitable cylinder which has

threaded detachable connection with the base 6. The upper end of the cylinder is provided with a removable cap 7 having a central opening therein to accommodate the plunger rod 8. The upper end of this rod is equipped with a head 9 which serves as a suitable hand hold for the operation of the plunger.

10 designates the plunger proper of any desired construction which is secured upon the lower end of the rod 8, said rod projecting below the plunger and terminating in a needle point indicated at 11. A coil spring 12 of the requisite tensile strength is located around the rod 8 within the casing 5 and bears at its lower end against the plunger 10 and at its upper end against the cap 7 of the cylinder. Adjacent the upper end of the cylinder, the same is provided in its body wall with a suitable air outlet opening 13.

The base 6 is centrally formed with a passage 14, the intermediate portion of which is relatively narrow, said passage being flared at its upper end, as indicated at 15, to provide a seat for the needle point 11 of the plunger rod 8. This upper flared end of the passage 14 opens into a circular chamber 16 formed in the base 6 in which the lower end of the cylinder 5 is detachably mounted, 80 as above stated. The lower end of the passage 14 on the opposite side of its narrow central portion is also flared as indicated at 17 to provide a seat for the valve ball 18. 19 indicates a connecting nipple which has one of its ends threaded in the head 6 and the other end thereof designed for detachable connection with the intake manifold of the engine. This nipple is provided with an interior annular shoulder 20 against which one end of a valve spring 21 seats. The other end of this spring bears against the valve ball 18 and normally acts to yieldingly hold said valve upon its seat. The base 6 is further formed with a laterally 100 projecting nipple 22, the bore of which is in communication with the chamber 16 in the upper end of the base. A pipe connection 23 is adapted for detachable threaded engagement at one of its ends upon the nipple 22, said connection being provided with a suitable coupling member 24 for this purpose. In this coupling member a valve ball 25 is arranged and is yieldingly held upon its seat 26 by means of the spring 27. This 110

105

2
valve normally closes communication between the hose or other flexible connection 23 and the chamber 16 of the cylinder base 6. The other end of the pipe 23 is adapted 5 to be connected to a T coupling 28 which in turn is connected to the gasoline supply tank indicated at 29. To the laterally extending arm of this coupling, the pipe 30 is connected, said pipe supplying the gasoline 10 from the tank 29 to the carburetor, (not shown).

From the above description of the construction of our invention, its operation will be understood as follows:—Assuming that 15 the several parts of the priming device are in their normal positions, as shown in Fig. 2 of the drawing, upon an upward pull by the operator of the plunger 10, the coil spring 12 is, of course, placed under compression. 20 The upward movement of the plunger creates a suction through the chamber 16 of the cylinder base 6 and moves the valve ball 25 to an open position against the action of the spring 27. Gasoline is thus permitted 25 to pass from the connection 23 into the chamber 16 and downwardly through the passage 14 in the cylinder base. It is temporarily held against movement into the manifold by the valve ball 18, but upon the 30 release of the plunger, the spring 12 will immediately act to force the same downwardly and the pressure of said plunger upon the gasoline causes the valve 18 to open, thus permitting the fuel to pass 35 through the base 6 and the coupling nipple 19 into the manifold and from the latter to the several engine cylinders through the intake ports thereof. When the plunger is 40 in its normal position, the needle point 11 of the plunger rod 8 fits tightly in the upper end of the passage 14 and closes the same, thus preventing leakage of gasoline into 45 the manifold of the engine. The nipple 19 is preferably provided with an opening 31 through which air may enter and be carried 50 by and with the gasoline through the nipple to the several engine cylinders. The quantity of air entering through this opening may be regulated by the adjustment of 55 the sleeve 32 arranged upon the nipple, said sleeve being preferably constructed of metal or other friction material and having an opening 33 which, by turning the sleeve, may be disposed in full or partial registration with the opening 31.

From the foregoing description taken in connection with the accompanying draw-

ings, it is believed that the construction, manner of operation and several advantages of our improved primer for internal combustion engines will be clearly and fully understood. Owing to the extreme simplicity of the device, it will be appreciated that the same can be produced at small manufacturing cost and will not add materially to the selling price of motorcycles or other vehicles upon which the same is applied.

The device may be easily operated with a minimum of manual labor to quickly and thoroughly prime the engine cylinders.

It will, of course, be understood that while in the foregoing, we have specifically referred to the construction and arrangement of the several parts employed, these elements are susceptible of various minor 75 changes and we reserve the privilege of resorting to all such legitimate modifications that may be fairly embodied in the spirit and scope of the invention, as claimed.

What we claim is:—

In a priming device for internal combustion engines, a base provided with a passage centrally constricted and flared at its opposite ends, one end of the base being provided with a chamber with which the passage communicates, a cylinder threaded in said chamber, a plunger to operate in said cylinder including a rod having a needle point on one end engaging with one of the tapered ends of said passage, a spring arranged in the cylinder upon said rod and normally holding the point of the rod in the passage, a spring seated valve arranged in the other tapered end of the passage, a nipple connected to the base at the latter end of the passage and adapted for connection to the intake manifold of an engine, means for connecting the chamber of said base to a gasoline supply reservoir, and a spring seated valve in said connection normally closing communication between the same and said chamber and adapted to be opened by suction in the movement of the plunger in the cylinder against the action of said spring, the release of the plunger operating to force the gasoline from the chamber through the base to the manifold.

In testimony whereof we hereunto affix our signatures in the presence of two witnesses:

LELICE E. JOHNSON.
HARRY M. MATHERS.
